UNITED STATES PATENT OFFICE

128,614

DESIGN FOR A SCABBARD

Edwin L. Beckwith, Brookline, Mass.

Application December 23, 1939, Serial No. 89,102

Term of patent 14 years

To all whom it may concern:

Be it known that I, Edwin L. Beckwith, a citizen of the United States, and a resident of Brookline, in the county of Norfolk and Commonwealth of Massachusetts, have invented a new, original, and ornamental Design for a Scabbard, of which the following is a specification, reference being had to the accompanying drawing, forming a part thereof in which,

Fig. 1 is a plan view of a scabbard showing my new design; the outline of the fitting being conventional and shown in dash lines,

Fig. 2 is a corresponding view in side elevation,

Fig. 3 is a view in cross section on the line 3—3 of Fig. 1, and

Fig. 4 is a view in cross section on the line 4—4 of Fig. 1.

The dominant feature of my novel design consists in a scabbard body which has longitudinal shoulders defining marginal ribs along both edges of the scabbard, the ribs merging inwardly through convex surfaces into a wide flat centrally disposed face, both the ribs and said face presenting the appearance of a flat, coarse, woven fabric surface encased beneath the surface of a smooth partially transparent shell.

I claim:

The ornamental design for a scabbard, substantially as shown and described.

EDWIN L. BECKWITH.
